UNITED STATES PATENT OFFICE.

GEORGE ALBERT LYON, OF PHILADELPHIA, PENNSYLVANIA.

BUFFER FOR MOTOR VEHICLES.

Application filed January 19, 1921, Serial No. 438,294. Renewed September 14, 1923.

To all whom it may concern:

Be it known that I, GEORGE ALBERT LYON, a citizen of the United States, and resident of Philadelphia, county of Philadelphia, State of Pennsylvania, have made a certain new and useful Invention Relating to Buffers for Motor Vehicles, of which the following is a specification, taken in connection with the accompanying drawing, which 10 forms part of the same.

This invention relates especially to resilient strip automobile buffers or bumpers of the general type covered by the Lyon Patent No. 1,198,246 of September 12, 1916, 15 which shows in some of the buffers upwardly bent portions adjacent the overlapping connecting portions of the buffer strips. Since many automobiles are constructed with low hung frames, it is often desirable 20 to bring at least parts of the front or impact receiving members of the buffer up above the buffer supporting arms and for this purpose it is desirable to form bent or arched up portions of the overlapping or reinforcing resilient strips so that several upwardly 25 arched or extending contact portions may be formed, preferably adjacent the clamping devices used to connect these overlapping reinforcing front strips. It is also desirable 30 in many cases to have these arched up or contact portions of the front strips which may be advantageously formed adjacent the strip ends in many cases twined or twisted around the cooperating connector portions 35 of the buffer strips and one or both of these end portions may be twisted around the cooperating connector portions so as to still further reinforce and strengthen the same when securely clamped or connected thereto. 40 and if desired a central clamping device may also be used in some cases adjacent the central part of these overlapping front strips. In some cases the connector end portions of the front strips may be diagonally arranged 45 so that when the bent or arched portion is arranged above, this connector end may form a downwardly projecting contact portion below the cooperating connector portion of the other resilient strip to which it 50 may be clamped or connected as by a U-bolt or other clamping device. In many cases however, a stronger and neater connection may be formed by bending the end connector portion of the overlapping buffer strips into 55 line with the cooperating connector portion to which it is clamped or connected. This

also somewhat facilitates the lateral adjustment of the spring strip elements in adjusting the width of the buffer to fit different widths of automobile frames. 60

In the accompanying drawing showing in a somewhat diagrammatic way various illustrative embodiments of the invention.

Fig. 1 is a front perspective view showing one form of buffer. 65

Fig. 2 is a corresponding view showing another arrangement; and

Fig. 3 shows a different adjustment thereof. 70

Figs. 4 to 7 are front perspective views showing different illustrative buffers; and

Fig. 8 is a transverse sectional view taken substantially along the line 8—8 of Fig. 7.

The vehicle buffer may advantageously be formed of two strips of resilient material such as tempered steel which may be one-quarter to three-eighths of an inch thick and one and three-quarters to two and one-half inches wide more or less and each strip may if desired be formed with integral end loop 75

resilient portions and attaching arms or portions adapted to be clamped or otherwise connected to the vehicle. The front or impact receiving portions 2 of the buffer may for instance be formed integral there- 80

with the end loop 3 and the attaching arm 4, while the other front strip may have a corresponding end loop 5 and attaching arm or member 6. These buffer front strips preferably have upwardly bent or arched por- 85

tions such as 8, 11 which may be most conveniently formed adjacent the ends 9, 12 of the strip as by bending or arching upward a limited portion of the overlapping spring strips adjacent their ends, so that upwardly 90

extending contact portions may be formed extending several inches above the normal or straight lateral portions 1, 2 of the buffer front. It is desirable in many cases to bend the end connector portion of each of these 95

front strips substantially into line with the cooperating connector portion of the other strip to which it may be connected, so that these substantially straight overlapping ends 100

9, 12 several inches long may be provided for engagement with the clamping or securing devices 14, 15 which may advantageously be of the general type described in said patent. By having the upward arch or bend start 105

at such a point as 7 adjacent the center of the buffer front, a pleasing appearance is produced by the overlapping diagonal cen- 110

tral portions of the buffer, which may if desired be connected by a clamping device such as 13, rigidly bolting together these diagonally overlapping portions such as 16. 5 It is also in many cases desirable to intertwine one or both of these ends or buffer front strips by twisting them around the cooperating connector portions of the other spring strip and for instance, the connector 10 end 9 may be twisted or bent around in front of the cooperating connector portion or strip 1, while the connector end 12 may be bent or twisted around behind the cooperating connector portion 2 of the buffer front. This 15 gives a still greater strength and rigidity and if desired these connector ends may be preliminarily forced or clamped together before the clamping or connecting devices of any suitable character are put in place and 20 tightened thereon. Of course, this arrangement allows the front strips to be laterally adjusted with respect to each other and a number of inches of lateral adjustment may be secured so as to enable the buffer to fit 25 the usual widths of commercial automobile frames.

This is shown in Figs. 2 and 3 in which generally similar upwardly arched buffer ends are shown as secured together in mutually reenforcing position but without intertwining or twisting the strip ends around the cooperating connector portions as shown in Fig. 1. In Fig. 2 the attaching members 4, 6 are shown as somewhat widely separated 30 so that the central diagonally overlapping portions meet at their upper edges at the point 19, considerably above the level of the comparatively straight lateral portions 17, 18 of the buffer front strips. When however, the strips are forced together considerably more as shown in Fig. 3, this central meeting point 20 is somewhat lower although the same general double arched or intertwined contour of the buffer front is still 40 present. Any suitable form of clamping or connecting device may of course be used to connect these overlapping reenforced portions of the buffer front and one piece malleable iron or wrought steel clamps of 45 the type shown in said Lyon patent are shown at 20, 21 for this purpose.

Fig. 4 shows another arrangement in which the buffer front strips 23, 24 which may be connected to the supporting members 4, 6 in any suitable or desired way may have formed adjacent their ends the upwardly bent or arched portions 25, 26 which may have diagonally arranged connector portions, so as to have downwardly projecting ends 28, 29 that may if desired extend considerably below the cooperating end portions or other strips to which they are clamped or connected. A simple and desirable form of connecting device for this 65 purpose may comprise the two U-bolt con-

nectors 30, 31 which may extend through these diagonally arranged connector ends and be tightened as by nuts 23, so as to form a tight connection and pleasing appearance especially when both of the straight or level 70 connector portions are arranged in front as illustrated. A lateral adjustment of the buffer front elements is possible in the same way in this case with a corresponding variation in the height of the meeting point 27. 75

Fig. 5 shows another arrangement in which the upwardly arched portions 36, 27 are arranged at some distance from the ends of the front strips. One of these resilient front strips 33 may for instance, have an upwardly bent or arched portion 36 extending upward an inch or so beyond the normal height of the strip and returning to this original level at about the point 44 adjacent the middle of the buffer front. The rest 80 of this front strip 35 may be straight as indicated so that its end 40 coincides in direction with the cooperating connector portion 34 of the other strip. The other strip 34 may have a corresponding upwardly arched portion 37 and straight end portion 38, 39, so that these overlapping reenforcing portions may be conveniently clamped together as by the end clamps 41, 43 and also if desired have a center clamp 42 of any suitable 85 construction.

Fig. 6 shows another arrangement in which the upwardly arched or bent contact portions are arranged outside or beyond the connecting or clamping devices, the front strip 45 having for example an upwardly arched or bent portion 46 adjacent its end 47 which may as indicated be twisted around back of the cooperating connector portion 48 of the other strip. This other front strip 48 may have a similar upwardly arched or bent portion 49 adjacent its end 50, which may be arranged behind the other front strip 45 and if desired clamped or connected thereto in addition to the adjustable 100 connecting or clamping devices 51, 52 encircling these strips inside of the upwardly arched or projecting clamping portions in 105 this instance.

Fig. 7 shows still another arrangement in which the upwardly extending contact portions are substantially straight or level and may if desired be arranged substantially in edgewise alignment with the cooperating portion of the other buffer front strip. One 110 of these front strips 53 may for example have a bent or twisted portion 59, so that the end portion 60 of the strip is brought substantially into the same vertical plane as the adjacent portion of the other strip 115 54, the lower edge 61 of this end 60 being substantially in contact with the upper edge with the strip below. The buffer front strip 54 may have a correspondingly bent portion 55 so as to carry the end 56 of this 120

strip up above the corresponding portion of the other front strip 53, the curved end 57 being formed on this strip if desired which may have its lower edge 58 substantially in engagement with the upper edge with the strip below if this is desired. A special form of clamp shown in Fig. 8 may be used to connect these strips in edgewise overlapping position and one of these clamps 62, 63 may encircle the two strips 53, 56 and be tightly clamped around them as by the bolt 65, so as to securely hold the parts in this position in connection if desired with any other form of connecting and clamping device.

This invention has been described in connection with a number of embodiments, forms, proportions, parts, arrangements, materials, methods of connection and use, to the details of which disclosure the invention is not of course to be limited, since what is claimed as new and what is desired to be secured by Letters Patent is set forth in the appended claims.

25 I claim—

1. The automobile buffer consisting of two integral spring steel strips having greater vertical width than thickness and each comprising an attaching member, an intermediate end loop and an impact receiving buffer front member arranged in overlapping reenforcing cooperation with the other front member of the buffer, each of said buffer front members comprising an upwardly arched contact portion adjacent its end and having its end connector portion bent substantially into line with the cooperating connector portion of the other buffer front member, each of said end portions being twisted around the other buffer front member and encircling clamping members connecting said cooperating connector portions in laterally adjusted intertwined position.

45 2. The automobile buffer consisting of two integral spring steel strips having greater vertical width than thickness and each comprising an attaching member, an intermediate end loop and an impact receiving buffer front member arranged in reenforcing cooperation with the other front member of the buffer, each of said buffer front members comprising an upwardly arched contact portion adjacent its end and having its end connector portion bent substantially into line with the cooperating connector portion of the other buffer front member, and clamping members connecting said cooperating connector portions in laterally adjusted position.

60 3. The automobile buffer comprising two integral resilient steel strips having greater vertical width than thickness and each comprising an attaching member, an intermediate end loop and an impact receiving buffer

front member arranged in reenforcing cooperation with the other front member of the buffer, each of said buffer front members comprising adjacent its end a bent up portion extending above its end loop and attaching member and having its end connector portion bent substantially into line with the cooperating connector portion of the other buffer front member, at least one of said end portions being twisted around the other buffer front member and clamping devices connecting said cooperating connector portions in laterally adjusted position.

4. The automobile buffer comprising two integral resilient steel strips and each comprising an attaching member, an intermediate end loop and an impact receiving buffer front member arranged in reenforcing cooperation with the other front member of the buffer, each of said buffer front members comprising adjacent its end a bent up portion extending above its end loop and attaching member and clamping devices connecting said cooperating connector portions in laterally adjusted position.

5. The automobile buffer comprising resilient steel strips and comprising an attaching member, an intermediate end loop and an impact receiving buffer front member arranged in reenforcing cooperation with the other front member of the buffer, each of said buffer front members comprising adjacent its end a bent up portion extending above its end loop and attaching member and clamping devices connecting said cooperating connector portions in laterally adjusted position.

6. The automobile buffer formed of resilient steel strip having greater vertical width than thickness and comprising cooperating members each having an end loop and an impact receiving buffer front member arranged in overlapping reenforcing cooperation with the other front member of the buffer, each of said buffer front members comprising an upwardly arched contact portion adjacent its end and an end connector portion bent substantially into line with the cooperating connector portion of the other buffer front member adjacent its end loop and encircling clamping members disengageably connecting said cooperating connector portions in laterally adjusted position to fit different width automobile frames.

7. The automobile buffer formed of resilient steel strip having greater vertical width than thickness and comprising cooperating members each having an end loop and an impact receiving buffer front member arranged in overlapping reenforcing cooperation with the other front member of the buffer, each of said buffer front members comprising a vertically bent contact portion

adjacent its end to be connected with the co-operating connector portion of the other buffer front member adjacent its end loop and clamping members disengageably connecting said cooperating connector portions in laterally adjusted position to fit different width automobile frames.

8. The automobile buffer formed of steel strip having greater vertical width than thickness and comprising cooperating members each having an intermediate end loop and an impact receiving buffer front member arranged in overlapping reenforcing cooperation with the other front member of the buffer, each of said buffer front members comprising a vertically bent contact portion and an end connector portion bent substantially into line with the cooperating connector portion of the other buffer front member, and clamping members connecting said cooperating connector portions.

9. The automobile buffer formed of steel strip having greater vertical width than thickness and comprising cooperating members each having an attaching member, an intermediate end loop and an impact receiving buffer front member arranged in overlapping reenforcing cooperation with the other front member of the buffer, each of said buffer front members comprising a vertically bent contact portion adjacent its end and an end connector portion bent substantially into line with the cooperating connector portion of the other buffer front member, and clamping members connecting said cooperating connector portions.

10. The automobile buffer comprising two integral resilient steel strips having greater vertical width than thickness and each comprising an attaching member and an impact receiving buffer front member arranged in reenforcing cooperation with the other front member of the buffer, each of said buffer front members comprising a bent up portion extending above the adjacent portions of the member, and clamping devices connecting said cooperating buffer front members in laterally adjusted position.

11. The automobile buffer consisting of two integral spring steel strips having

greater vertical width than thickness and each comprising an end loop and an impact receiving buffer front member arranged in reenforcing cooperation with the other front member of the buffer, each of said buffer front members comprising an upwardly arched contact portion, and clamping members connecting said buffer front members in laterally adjusted position.

12. The automobile buffer comprising resilient steel strips and comprising attaching members and an impact receiving buffer front member arranged in reenforcing cooperation with another front member of the buffer, each of said buffer front members comprising a bent up curved portion, and clamping devices connecting said cooperating buffer front members in laterally adjusted position.

13. The automobile buffer comprising resilient steel strips and comprising an impact receiving buffer front member arranged in reenforcing cooperation with another front member of the buffer, one of said buffer front members comprising a bent up curved portion, and clamping devices connecting said cooperating buffer front members in laterally adjusted position.

14. The automobile buffer formed of resilient steel strips having greater vertical width than thickness and comprising cooperating members each having an end loop and an impact receiving buffer front member connected in overlapping reenforcing cooperation with the other front member of the buffer, each of said buffer front members comprising an upwardly arched contact portion and an end connector portion bent substantially into line with the cooperating connector portion of the other buffer front member adjacent its end loop.

15. The automobile buffer comprising two integral resilient steel strips and each comprising an end loop and an impact receiving buffer front member connected in reenforcing cooperation with the other front member of the buffer, each of said buffer front members comprising adjacent its end a bent up portion extending above its end loop.

GEORGE ALBERT LYON.
